Assistant Examiner — Lynette Marie Sample

(57) **CLAIM**

The ornamental design for a coffee capsule storage display rack, as shown and described.

DESCRIPTION

FIG. 1 is a front, top perspective view of a coffee capsule storage display rack, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another front, top perspective view thereof, shown in use with environmental subject matter of exemplary coffee capsules; and,

FIG. 10 is a front elevation view thereof.

(Continued)

The evenly dashed lines are shown for the purpose of illustrating both parts of the coffee capsule storage display rack as well as environmental subject matter. None of the dashed lines form part of the claimed design.

1 Claim, 10 Drawing Sheets
